UNITED STATES PATENT OFFICE.

CHARLES T. WESTLAKE, OF ST. LOUIS, MISSOURI, ASSIGNOR TO TRANSOM DRAFT GEAR COMPANY, OF ST. LOUIS, MISSOURI, A CORPORATION OF DELAWARE.

DRAFT-GEAR FOR RAILROAD-CARS.

No. 854,132.

Specification of Letters Patent.

Patented May 21, 1907.

Application filed March 11, 1907. Serial No. 361,787.

To all whom it may concern:

Be it known that I, CHARLES T. WESTLAKE, a citizen of the United States, residing at St. Louis, in the State of Missouri, have 5 invented a new and useful Improvement in Draft-Gear for Railroad-Cars, of which the following is a specification.

My invention relates particularly to draft-gear applied to a railroad car forward of the 10 truck center, in which case when coupling cars on a curve difficulty is frequently experienced in inserting the knuckle pins for locking the engaged knuckles owing to the excessive angle of the draw-bars to their normal 15 central position, and my invention has for its object to obviate this objection by reducing the angle of the draw-bars, within ordinary limits of lateral movement, to the same angle or thereabout, as if they were 20 pivoted at the said center.

The invention consists in features of novelty as hereinafter described and claimed, reference being had to the accompanying drawing forming part of this specification, 25 whereon,

Figure 1, is a top plan view of the end portion of a metallic car underframe having my improved draft-gear applied thereto forward of the truck center; Fig. 2, a vertical longitudinal section through the underframe on line 2, 2, in Fig. 1, showing the draft-gear partly in corresponding section, and partly in side elevation, and Fig. 3, a diagrammatic top plan view showing geometrically the 30 relative position of the parts of the draft-gear when the draw-bar is in its normal central position, and when moved laterally to an angle of 5 degrees on one side thereof.

Like letters and numerals of reference denote like parts in all the figures.

a represents the end portion of a metallic car underframe, comprising the middle and side longitudinal sills 1, and 2, respectively, broken away, to which is fixed the combined double body-bolster 3 and forward end frame 4, the body-bolster 3 being perforated centrally at x for the king-bolt of the truck (not shown) in the usual well-known manner.

Riveted preferably, to the underside of the 45 middle longitudinal sills 1 at a suitable distance forward of the truck center x, is a block b to which is applied a suitable draft-gear, preferably that for which Letters Patent of the United States were granted to Harry M.

Plager, January 23, 1906, Number 810,805, 55 for improvement in draft-gear for railroad cars, in which front and rear springs respectively, are used without follower-plates, on each side of the longitudinal center line of the car, the front springs having their housings in the front side of the body-bolster and in the rear end face of the draw-bar extension, and the rear springs having their housings in the rear side of the bolster and in the yoke which is coupled at its ends to the 60 draw-bar extension on each side of the said center, and passes through openings formed therefor through the web of the bolster. In the present case a similar arrangement of these parts of the draft-gear is used, except 65 that the block b having the vertical web 5 is substituted for the bolster and its web, and a cross-bar c for the inner end of the draw-bar extension in the said patent, 6, 6', being the front and rear springs respectively on each 70 side of the longitudinal center line of the car, the front springs 6, having their housings 7 at one end in the front side of the web 5, and at the other end in the rear face of the cross-bar c, and the rear springs 6' having their housings 7' at one end in the rear side of the web 5, and at the other end in the inner face of the yoke 8 which straddles the springs 6, 6', and web 5, and is coupled at the ends to the 75 cross-bar c. To the cross-bar c at an equal 80 distance on each side of the said center line, is coupled by a pin 11, one end of a horizontally arranged link d having its other end coupled by a pin 12 to the rear end portion of the draw-bar e, which is suitably spaced 85 apart from the cross-bar c in the same horizontal plane therewith, and provided at its 90 forward end with the usual coupler f.

The links d are preferably arranged so that, when the draw-bar e is in its normal 95 central position, or in central alinement with the longitudinal center line of the car and truck center x, a line drawn from each joint 11 and 12 of one link d to the corresponding joint of the other link d, is at right angles to, 100 and bisected by the said center line, and that a line drawn through the joints 11 and 12 of each link d longitudinally therewith will pass through the truck center x.

In operation, on the lateral movement of 105 the coupler f to either side of its normal central position, within the ordinary limits of deviation, the draw-bar e will be constrained

by the consequent travel of the joint pins 12 in the same direction along the respective arcs described by the links *d* about their pivots 11, to assume an angle or position 5 with its longitudinal center in alinement, or thereabout, with the truck center *x*, instead of the larger angle of deviation as would be the case if moved laterally from the block *b* as its pivotal point without the intervening 10 links *d*.

What I claim as my invention and desire to secure by Letters Patent is:

In a car draft-gear having its pivotal point forward of the car truck center, the combination 15 of a spring, a housing for the spring fixed to the car, a cross-bar adapted to engage one end of the spring, a yoke coupled to the cross-bar and adapted to engage the other end of

the spring, a draw-bar spaced apart from the cross-bar and having a suitable coupling, and 20 two links adapted to connect the said bars together, one on each side of the longitudinal center line of the car, so that, on the lateral movement of the coupler from its normal central position, the angle of intersection 25 ordinarily made by the longitudinal center line of the car with that of the draw-bar when pivoted at the said point forward of the truck, is reduced to the same angle or thereabout, as if the pivotal point of the 30 draw-bar was at the truck center, substantially as described.

CHARLES T. WESTLAKE.
